UNITED STATES PATENT OFFICE.

GURDON G. WOLFE, OF TROY, NEW YORK, ASSIGNOR TO THE FULLER & WARREN COMPANY, OF SAME PLACE.

DESIGN FOR A FIRE-PLACE HEATER.

SPECIFICATION forming part of Design No. 17,209, dated March 22, 1887.

Application filed February 18, 1887. Serial No. 221,223. Term of patent 14 years.

To all whom it may concern:

Be it known that I, GURDON G. WOLFE, of the city of Troy, county of Rensselaer, State of New York, have invented and produced a new and useful Design for Fire-Place Heaters, of which the following is a specification.

My design relates to the form and ornamentation of fire-place heaters, and as the same is shown in the accompanying photograph, forming a part of this specification, and in which photograph the several parts of the fire-place heater are designated by letter reference and the ornamentation by figures.

The main features of my design consist in the particular ornamentation of the frame, top, front, and sides of a fire-place heater, as hereinafter described, and as appears in the illustrations thereof.

The letter F designates the fire-place-heater frame, which is composed of the corner-pieces f' f' and the arch-form reversing ovolo molding f'', having a plain surface. The corner-pieces each have rectilinear top edges, 1, and vertical side edges, 2, and the inner curved edge, 3, with the latter adapted to coincide as to form with the outer edge of the arch-form molding f'', which they join at each side of the arch. The sides of the molding f'', below where arched, are vertical, as indicated at 4, and these vertical edges of said molding are coincidently in line with the vertical side edges, 2, of the corner-pieces f' f''. The outer edges of the molding f'' and the outer rectilinear edges of the corner-pieces are ornamented by a fretted fillet, 5, and the field of the corner-pieces is ornamented with a centrally-arranged Corinthian scroll figure, 6, and reversing and bifurcating side scroll figures, 7 7. The cap of the arch in the molding f'' is ornamented with a relief gargoyle figure, 7 1/2, and radially-arranged curls. If desired, the corner-pieces f' f'' of the frame, where their straight side and top edges meet at right angles, may be rounded off in such manner as will not affect the general appearance of the design produced by the said curve pieces and the arch-form molding.

The top of the furnace T has the form of a flattened dome, d, divided diametrically on a line parallel with the face of the frame F, and the exterior surface of this top is ornamented

with the radiate figures 8, the scrolls 9, and the ovolo molding 15, with the filleted and fretted ogee molding 16 immediately below the said ovolo molding.

The heater-top platform T' is made to have upon its outer edge a downwardly-beveled band-molding, 17, and this edge subtends the body part of the furnace below it, and at the front has the form of two reversing ogee curves, 18 19. It is notched at the corners, as indicated at 20, before returning to the frame, and below the overhang is made with the fretted downwardly and inwardly extended ogee molding 21, connecting at its lower edge by a fillet, 14.

The furnace-front D has the form of two reversing cyma-recta curves, 22 22, and the sides S have an ovoло form, 23, with wave intrusions 24. The sides and front of the furnace between the upper and lower doors are ornamented with the plain ogee molding 25, fillets 26 26, and fretted fillet 27.

The upper doors, D' D', of the front are ornamented alike and are made to conform to the reversing cyma-recta curves of the front in their shape. These doors each have the frame 28, having a vertical center stile, 15, and a horizontal stile, 29, arranged to divide the frame area into panes. These panes 30 80 are ornamented by the vine-form scrolls 31, bifurcating at or about the center of each pane, one curve of the scroll returning to the frame side and the other curving to connect with the stile at the opposite side of the pane, and 85 each of the panes having fronds.

The lower doors, D'' D'', of the front have filleted frames 32, and the interior area of the frame of each of these doors is divided up by means of a central vertical stile and a horizontal stile 90 or sash-bar into panes, each of the latter being ornamented interiorly with two vine-form scrolls, 17, having frond ornaments, and with the two scrolls of each pane connecting centrally.

The doors D' D' at the top and bottom of the sides of the furnace each have a filleted frame, the area of which is divided off by a horizontal sash-bar and vertical stile into panes, the interior of each of which latter is 100 ornamented with a scroll, 64.

The base B has an overhanging top, 36, and

upon its outer edge an ogee molding, 37. The edge of this top molding at the front has the form of two reversing cyma-recta curves. It is notched at the corners as it returns from the front to the frame, as indicated at 38. The base B is molded at the bottom of its front and sides with a platform, 39, a downwardly outwardly beveled ribbed and frontwardly extended molding, 40, that is notched at the corners 41, from whence it runs along the side panels, P. The sides of the base B' are ornamented by alternatingly-arranged plain and fluted squares 42 43 and rosette figures 44, a top fret-molding, 45, and a bottom fluted molding, 46, and flat band 16.

The door D' of the base at the front has the same ornamentation of alternatingly plain squares 47 and fluted squares 48 and rosettes 44, that are used in the sides of the base, with a fretted molding at the top 49 and a fluted molding, 50, at the bottom of the door, with the rosette figure 51 arranged on the front and center of the door.

The letter P designates the side panels formed between the outcurve of the furnace-front and the inner edge of the arch-form molding f'. These side panels are ornamented with top and bottom convolute fronded scrolls, 52 53, the intermediate filleted bars, 54 55 56, and the 30 interiorly-waved oval figures 57 58 between said bars.

The letter H designates the hinge-plate of the upper and lower front doors of the furnace, which is ornamented with scroll figures 65 on 35 its front where opposite the front door, and with reversing scrolls 66 66, connecting with the scrolls of the side doors, D', where extending frontwardly from the latter.

The form of the corner-pieces f' f'' and the 40 form of the arch-form molding f' being retained, and they being arranged with reference to each other to produce an ornamental effect, as shown, other surface ornamentation than that shown may be used, provided the ornamental effect produced by the form of these parts is not changed thereby.

Having thus described my design, what I claim, and desire to secure by Letters Patent, is—

50 1. In a design for a fire-place heater, the frame F, consisting of the corner-pieces f' f'', having fretted outer edges and ornamented on their fields with a Corinthian scroll, 6, having reverse side scrolls, 7, and the arch-form molding f', having a plain surface and fretted border and ornamented with the centrally-arranged gargoyle figure, as shown and described.

55 2. In a design for a fire-place heater, top T, consisting of the flattened dome d, divided dia-

metrically in a line parallel with the face of the fire-place frame, and having on its upper surface the radiate figures 8, scrolls 9, ovolo molding 15, filleted and fretted ogee molding 16, and overhanging platform T', having the beveled band-molding 17 on its edge, and the downwardly and inwardly extended and fretted ogee molding 21 and fillet 14, as shown and described.

3. In a design for a fire-place heater, the front D and sides S, the front having an exterior composed of two reversing cyma-recta curves, 22 22, and the sides having an ovolo form, 23, with wave intrusions 24, as shown and described.

4. In a design for a fire-place heater, the upper doors, D' D', consisting of a frame area divided up by a vertical stile and a horizontal sash-bar, panes 30, with the latter containing vine-form scrolls 31, made to bifurcate at about the center of each pane, with one curve of the scroll curving in return contour and the other branch curving to the opposite stile or side of the frame, as shown and described.

5. In a design for a fire-place heater, the base B, consisting of the platform-top 36, 85 molded and notched and having the form on its outer edge as shown and described, the base front having the exterior form of two reversing cyma-recta curves, and notched where joining the sides, the sides S, ornamented with 90 alternatingly fluted and plain squares and rosette figures thereon, the top fret-molding, 45, and the bottom fluted molding, 46, and band-molding 16, extending around the front and sides, as shown and described.

6. In a design for a fire-place heater, the base doors, D', consisting of a contour conforming to that of the base, and having the top fret-molding, 49, the bottom fluted molding, 50, 100 alternatingly plain and intermediately-arranged squares 47, fluted squares 48, and rosette figures 44, as shown and described.

7. The design for the fire-place heater, consisting of the frame F, the form and ornamentation of the top T, the form and ornamentation of the front D and sides S, the doors D' D', the doors D', the form and ornamentation of the base B, base doors, D', side doors, D', the side panels, P, and the ornamentation of the hinges H, as shown and described.

Signed at Troy, New York, this 7th day of July, 1886, and in the presence of the two witnesses whose names are hereto written.

GURDON G. WOLFE.
